United States Patent Office.

JOHN A. NICHOLS. OF PATERSON, NEW JERSEY.

Letters Patent No. 83,302, dated October 20, 1868.

IMPROVEMENT IN VALVES FOR PUMPS.

The Schedule referred to in these Letters Patent and making part of the same.

To all whom it may concern:

Be it known that I, JOHN A. NICHOLS, of Paterson, in the county of Passaic, and State of New Jersey, have invented a new and useful Improvement in Pump-Valves; and I do hereby declare that the following is a full, clear, and exact description thereof, which will enable others skilled in the art to make and use the same, reference being had to the accompanying drawings, forming part of this specification, in which—

Figure 1 is a vertical cross-section of fig. 2, through the line *x x*, showing the manner in which the valve operates on its seat, with the rubber facing on the valve and stop.

Figure 2 is a horizontal section of fig. 1, through the line *y y*, showing the operation through the valve and valve-seat, with the form of the casing.

(The method in which the valves operate in combination with each other is shown in figs. 3 and 4 in red color.)

Figure 3 is a section of fig. 4, through the line *z z*, and

Figure 4 is a section of fig. 3, through the line *z' z'*.
Similar letters of reference indicate like parts.

This invention relates to an improvement in the method of constructing pump-valves, being more particularly designed for the pumps of steam fire-engines, but which may be applied to other pumping-engines; and it consists in constructing the valves, for the purposes intended, in the manner hereinafter described.

The case consists of two parts, A A', the former being the outer cylindrical shell, having perforations, C, in its bottom, which forms the seat for the valve B. The part A' consists of a perforated plate, B', covering the top of the shell, and from which depends an annulus, G, having upon its under side rubber packing, F', and which forms a stop for the upward movement

of the valve. The annulus G is connected to the plate B' by radial partitions *a*, to the inner edges of which is attached a sleeve, *h*, forming a guide for the valve-stem E. The valve B is perforated at C', and faced with rubber packing F.

When the valve is raised, the water flows through perforations C around the outside of the valve, and also through perforations C' in the valve, the annulus G being so arranged as not to interrupt the course of the water.

By the arrangement of the rubber F F', as represented, the noise or click produced by the contact of metallic surfaces is avoided, while leakage of the valve is prevented.

The manner in which the valves operate in combination with each other, when more than one are used, and with the pump, is seen in the figs. 3 and 4.

J is the barrel of the pump, and the piston is moving in the direction of the arrow. The lower valve is closed, while the upper one is open, and the water is being discharged through the orifice *k*.

By this method of constructing and arranging the valves, it will be seen that a very large quantity of water may be thrown through them, while their movement is very slight.

The advantages of this arrangement for fire-engine pumps will be readily understood and appreciated by all interested in the subject.

Having thus described my invention,
I claim as new, and desire to secure by Letters Patent—

The valve-case A A', in combination with the valve B, constructed and arranged to operate as described.

JOHN A. NICHOLS.
